(57) **CLAIM**

The ornamental design for a cupcake box with heart-shaped window, as shown and described.

DESCRIPTION

FIG. 1 is a front, right, and bottom perspective view of a cupcake box with heart-shaped window, showing my design.

FIG. 2 is a rear, left, and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of the encircled area 9 of FIG. 1. The broken lines are shown for the purpose of designating the area of the enlarged view of FIG. 9 and form no part of the claimed design.
